UNITED STATES PATENT OFFICE.

VAHÉ SOULTANIAN, OF LEEDS, ENGLAND, ASSIGNOR TO THE BLACKBURN AEROPLANE AND MOTOR COMPANY, LIMITED, OF OLYMPIA, LEEDS, ENGLAND.

CLAMPING DEVICE OR JIG.

1,318,814.

Specification of Letters Patent.

Patented Oct. 14, 1919.

Application filed October 2, 1918. Serial No. 256,578.

To all whom it may concern:

Be it known that I, VAHÉ SOULTANIAN, a subject of and a citizen of Russia, residing at Roundhay, Leeds, Yorkshire, England, 5 have invented certain new and useful Improvements in Clamping Devices or Jigs, of which the following is a specification.

The present invention refers to an improved clamping device or jig, the object 10 of which is to grip and hold a body, such as a cylinder or a polygonal prism by gripping its cylindrical or polygonal sides in such manner that such bodies, gripped from time to time, shall be automatically 15 brought into the same position as each other, even although the external diameters of the bodies may vary somewhat in dimensions. Such a jig is particularly useful for positioning and holding such bodies during 20 axial drilling or tapping or the like.

The invention will be described with reference to the accompanying drawings, whereon Figure 1 is a side elevation of the clamping device or jig, Fig. 2 being a plan 25 view. Fig. 3 is an end elevation of the jig looking from the left of Fig. 1, Fig. 4 is an end elevation looking from the right of Fig. 1, and Fig. 5 is a vertical section on the line X—Y of Fig. 2 to show two oppositely threaded revoluble trunnions hereinafter referred to.

From a socket 1 formed with a base plate 2 there extend two vertical parallel pivot pins 3, 4, and pivotally mounted upon said 35 pins 3, 4 are two similar jaws 5 and 6, each jaw having extending rearward arms 7 and 8, so that one jaw is freely carried upon the pivot pin 3, and the other jaw is freely carried on the pivot pin 4. Each jaw is 40 formed on its gripping surface or face with a vertical V-shaped groove, the groove 5^x in the face of one jaw 5 being precisely similar to the groove 6^x in the face of the opposed jaw 6, see Fig. 2, and as shown a prism 45 such as 9 is intended to be gripped between the vertical and angular walls formed by the V-shaped grooves 5^x, 6^x of the jaws 5, 6.

In the constructional design illustrated, a plate 10 extends above the bosses of the 50 jaws, passes over the ends of the pivot pins 3, 4, and is suitably secured as by bolts.

The rearward arms 7, 8 are each forked and drilled vertically to each receive a revoluble trunnion 11, the trunnions being 55 drilled at right angles to their axes and screw-

threaded to receive a screwthreaded shaft 12, see Fig. 5, the shaft 12 being formed at one end with a right-handed thread and at the other end with a left-handed thread, and consequently the trunnions 11 are screw-threaded to correspond, and the axes of the trunnions 11 are parallel to the axes of the pivot pins 3, 4. A hand wheel 13 is fixed about centrally on the screw shaft 12 by which the latter shaft 12 can be revolved. 60

The screw shaft 12 according to this invention has freedom of movement in the direction of its axis, and therefore when a circular or polygonal prism 9 is gripped between the walls of the opposed V-shaped 70 grooves 5^x and 6^x of the jaws 5 and 6, the distance of the axis of such a prism from both of the axes of the pins 3, 4 will be equal.

Since an unlimited endwise motion of the screw shaft 12 would militate against the 75 rapid use of the device, it has been found convenient according to this invention, while allowing the screw shaft 12 sufficient free endwise adjustment, yet to provide some limiting device. For this purpose the rim 80 of the hand wheel 13 passes between the forked ends 14 of a member 15 mounted on the base plate, there being a clearance 16 between the forked members 14 and the surface of the rim of the wheel 13, so that although the shaft 12 is held against any considerable endwise motion the clearance space 85 16 between the members 14 and the rim of the wheel 13 allows a limited amount of endwise motion. This freedom of endwise adjustment of the screw shaft 12 is important, 90 vises for gripping tubes being already known comprising two gripping jaws independently pivoted on separate pivots, the meeting faces of the jaws having V-shaped 95 grooves and having rearward arms drawn together by a screwthreaded shaft which is held by some suitable stationary bearing against endwise motion while being permitted to be revolved, whereas it will be observed in the present invention that the screw shaft 12 is permitted endwise adjustment, whereby an automatic centering of the prism gripped is obtained instead of a forced centering such as would be obtained 100 if no such endwise motion of the screw shaft was permitted.

With the apparatus constructed according to this invention by placing a prism such as 9 between the jaws 5 and 6 and turning 110

or spinning the wheel 13 to close the jaws the prism will be acted upon by the inclined walls of the opposed V-shaped grooves 5^x, 6^x, and as the jaws are brought together 5 their faces will be caused to have automatic longitudinal adjustment relatively to each other, governed by the external configuration of the prism 9 and permitted by the free endway motion of the screw shaft 10 12; consequently when the prism 9 is removed and another similar body placed between the jaws and gripped its axis will be brought to the same position as that of the first body, and when two prisms of slightly 15 differing diameters are successively clamped, they are centered in one coordinate with geometrical accuracy, and thus the drilling and tapping of such bodies is greatly facilitated, and moreover the tools will always 20 act upon the axis of the body, and therefore the breakage of drills and taps in carrying out such operations is greatly lessened, which at the present time is very important as regards rapid and economical produc- 25 tion.

What I claim as my invention and desire to secure by Letters Patent is:—

1. A clamping device or jig for holding and centering cylindrical or polygonal 30 prisms; comprising a base plate, two vertical pivot pins carried therefrom, a jaw revolvably mounted on each pivot pin, each jaw having a rearwardly extending arm, and each jaw having on its gripping face a precisely similar vertical V-shaped groove between the vertical angular walls of which opposed V-shaped grooves the prism is to be gripped and centered, a vertical revoluble trunnion carried at the rearward end of each 35 rearward jaw arm, each trunnion having a through screwthreaded hole at right angles to its axis the direction of the thread of one trunnion being opposite to the direction of the thread of the other trunnion, a shaft 40 having opposite handed screw threads to respectively engage the screwthreaded holes of said two trunnions, and means for revolving said screw shaft to cause said jaws to approach each other to grip the prism located between the inclined walls of said V-shaped 45 grooves, said shaft being free to have endway motion to permit said jaws having longitudinal adjustment relatively to each other 50 governed by the contact of the external surface of the prism gripped with the inclined walls of the opposed V-shaped grooves.

2. A clamping device or jig for holding and centering cylindrical or polygonal 60 prisms; comprising a base plate, two vertical pivot pins carried therefrom, a jaw revolvably mounted on each pivot pin, each jaw having a rearwardly extending arm, and each jaw having on its gripping face a precisely similar vertical V-shaped groove be-

tween the vertical angular walls of which opposed V-shaped grooves the prism is to be gripped and centered, a vertical revoluble trunnion carried at the rearward end of each rearward jaw arm, each trunnion having a 70 through screwthreaded hole at right angles to its axis the direction of the thread of one trunnion being opposite to the direction of the thread of the other trunnion, a shaft having opposite handed screw threads to respectively engage the screwthreaded holes of said two trunnions, means for revolving said screw shaft to cause said jaws to approach each other to grip the prism located between the inclined walls of said V-shaped grooves, 80 said shaft being free to have endway motion to permit said jaws having longitudinal adjustment relatively to each other governed by the contact of the external surface of the prism gripped with the inclined walls of the 85 opposed V-shaped grooves, and means for limiting the endway motion of said screw shaft.

3. A clamping device or jig for holding and centering cylindrical or polygonal 90 prisms; comprising a base plate, two vertical pivot pins carried therefrom, a jaw revolvably mounted on each pivot pin, each jaw having a rearwardly extending arm, and each jaw having on its gripping face a precisely similar vertical V-shaped groove between the vertical angular walls of which opposed V-shaped grooves the prism is to be gripped and centered, a vertical revoluble trunnion carried at the rearward end of each 95 rearward jaw arm, each trunnion having a through screwthreaded hole at right angles to its axis the direction of the thread of one trunnion being opposite to the direction of the thread of the other trunnion, a shaft 100 having opposite handed screw threads to respectively engage the screwthreaded holes of said two trunnions, a hand wheel fixed about centrally on said screw shaft for revolving the latter to cause said jaws to approach each other to grip the prism located between the inclined walls of said V-shaped 105 grooves, said shaft being free to have endway motion to permit said jaws having longitudinal adjustment relatively to each other 110 governed by the contact of the external surface of the prism gripped with the inclined walls of the opposed V-shaped grooves.

4. A clamping device or jig for holding and centering cylindrical or polygonal 120 prisms; comprising a base plate, two vertical pivot pins carried therefrom, a jaw revolvably mounted on each pivot pin, each jaw having a rearwardly extending arm, the meeting faces of said jaws each having a 125 coinciding vertical groove of V-shape formed therein to receive the cylindrical or polygonal prism to be gripped and centered, a vertical revoluble trunnion carried at the rearward end of each rearward jaw arm, each 130

trunnion having a through screwthreaded hole at right angles to its axis the direction of the thread of one trunnion being opposite to the direction of the thread of the other 5 trunnion, a shaft having opposite handed screw threads to respectively engage the screwthreaded holes of said two trunnions, a hand wheel fixed about centrally on said screw shaft for revolving the latter to cause 10 said jaws to grip or release the cylindrical or polygonal prism, and a member mounted on said base plate and having upstanding

forked ends between which the rim of said hand wheel passes, said forked ends of said member being spaced apart to permit said 15 hand wheel and said screw shaft to which said hand wheel is fixed having limited end-way motion.

In witness whereof I have hereunto set my hand in the presence of two witnesses.

VAHE SOULTANIAN.
